(57) **CLAIM**

The ornamental design for a wireless accessory for a communication device, as shown and described.

DESCRIPTION

FIG. 1 is an isometric view of a wireless accessory for a communication device showing my new design;
FIG. 2 is a front elevation thereof;

FIG. 3 is a rear elevation thereof;

FIG. 4 is a right side elevation thereof;

FIG. 5 is a left side elevation thereof;

FIG. 6 is a top plan view thereof; and,

FIG. 7 is a bottom plan elevation thereof.

The broken lines shown in FIGS. 1-7 represent environmental elements and form no part of the claimed design.
